UNITED STATES PATENT OFFICE.

ERNEST CROWTHER AND WILLIAM HENRY CROWTHER, OF PUDSEY,
ENGLAND.

SCRIBBLER OR CARDING-ENGINE.

SPECIFICATION forming part of Letters Patent No. 521,703, dated June 19, 1894.

Application filed December 12, 1893. Serial No. 493,514. (No model.)

To all whom it may concern:

Be it known that we, ERNEST CROWTHER and WILLIAM HENRY CROWTHER, subjects of the Queen of Great Britain, residing at Pudsey, 5 in the county of York, England, have invented a certain new and useful Improvement in Scribblers or Carding-Engines, of which the following is a specification.

Our invention relates to an improvement in scribblers or carding engines it being designed to insure the cleaning of the "workers" or card covered rollers of such machines.

It consists of an improved arrangement of the workers and of the combination there- 15 with of other card covered rollers or brushes whereby the accumulation of grease and dirt on the workers is in a great measure prevented and consequently the labor of keeping said workers clean is materially lessened.

20 To clearly explain our invention we illustrate it in the accompanying drawings, in which—

Figure 1 is a diagrammatic view of a single cylinder scribbler constructed according 25 to our invention. Fig. 2 is a similar view of a double cylinder scribbler, and Fig. 3 is a view illustrating a modification.

It will be seen that instead of as heretofore arranging around the main cylinder 1 (Fig. 1) 30 first a "worker," then a "stripper," then another "worker" and then another "stripper" and so on, we arrange the workers 2, 2, so that they are in contact with each other and also with the main cylinder, the centers of 35 said workers being in an arc of a circle drawn from the center of the main cylinder and in the angle or space above the workers where the circumferences of the workers converge we place, either in all of such spaces or prefer- 40 ably in alternate spaces a card covered roller 3 of small diameter for cleaning purposes, the teeth of the cards of the rollers 3 being preferably straight, that is to say without knee or bend. Instead however of said 45 rollers a card brush 4 of V section may be applied between the workers as illustrated in Fig. 3. These brushes are arranged above

and in contact with each pair of workers, and are provided with straight card teeth, shaped to fit the interstices between the workers for 50 the purpose of cleaning the same.

It is preferred to have the cleaners arranged in alternate spaces for the reason that then each worker is acted on by the cleaner, and yet there are only half as many cleaners 55 used as would be required to put one in each of said spaces above the workers.

It will be seen that the mass of fiber 5 is carried partially round each worker 2 and is then removed therefrom by the next worker 60 which rotates in the same direction and so passes through the machine until it is removed by a stripping roller 6 as shown in Fig. 1 or by a fly comb 6 as shown in Fig. 2 which is an illustration of a scribbler having two 65 cylinders 1. 1. and provided with our improvements.

What we claim is—

1. The combination with a scribbler or carding engine having a number of workers touching each other, arranged around the main drum of card covered cleaners, arranged above the workers, projecting into the angle where the circumferences of the workers converge, and in contact each with its two adjacent workers, for the purpose of cleaning the same, substantially as described. 75

2. The combination with a scribbler or carding engine, having a number of workers touching each other, arranged around the main 80 drum, of card covered rollers projecting into the alternate angles or spaces where the circumferences of the workers converge, arranged above the workers and in contact each with its two adjacent workers, for the purpose 85 of cleaning same, substantially as described.

In testimony whereof we have hereunto set our hands in the presence of two subscribing witnesses.

ERNEST CROWTHER.

WILLIAM HENRY CROWTHER.
